PIPE PILE CONSTRUCTION

William R. Marsden, Brooklyn, N. Y.

Application March 21, 1936, Serial No. 70,089

3 Claims. (Cl. 61—57)

This invention relates to new and useful improvements in pipe pile construction.

The objects of the present invention are to produce a pipe pile which will assure firm lateral earth support for the pile, in which the accumulation of a core of earth in the pipe is prevented and therefore the removal of detritus is obviated, and in which the driving edge of the pipe is protected against damage.

10 Some of these objects have been accomplished by prior pipe pile constructions of the so-called closed and open-ended types, but I am not aware of any construction embodying all the advantages here outlined.

15 In order more clearly to explain the nature of the invention I shall now describe one embodiment thereof with the aid of the drawing in which—

Fig. 1 is a vertical cross-section of my pipe pile construction;

20 Fig. 2 is a side elevation partially in section of the completed pile;

Fig. 3 is a plan view of the locking collar;

25 Fig. 4 is a vertical cross-section of the mandrel extension assembly; and

Fig. 5 is a side elevation of a modified type of spud point.

The pipe pile consists of an annular casing or pipe section 10 which encloses a mandrel 1.

30 The length of the mandrel may be increased by a mandrel extension such as 2. The lower edge of the pipe 10 is provided with a protective driving ring 3 to prevent its distortion by obstructions when driven into the ground. A heavy

35 driving spud 4 is attached to the lower end of the mandrel 1 by means of a flanged collar 13 which bears on a shoulder 6 formed in the spud 4. The shoulder 6 of the spud bears on top of the driving ring 3. The spud 4 has a

40 slightly tapered face 7, making contact over part of its length with the tapered inside face 8 of the ring 3. The lower end of the pipe section 10 contacts with the tapered outside of flange 11 of ring 3 and bears on the shoulder 12 of the latter.

45 A segmented locking collar 13 is held against the pipe 10 and the mandrel 1 by means of screws or the like. The purpose of this collar is to fasten together the pipe 10 and mandrel 1 and 50 prevent their separation by earth friction exerted on the pipe section 10 during the driving operation. Owing to the provision of this collar the pipe 10 may be driven into and withdrawn from the earth in unison with the mandrel 1.

55 The mandrel extension 2 is provided at its two

ends with flanged collars 14 and 15. A sleeve 16 fits within the collar 14. Locking pins 17 will penetrate within holes 17 in the sleeve 16 to hold together mandrel 1 and the extension 2. The number of extensions 2 that are necessary in driving a pipe pile is determined by the distance the pile has to penetrate into the earth before reaching rock. When the penetration exceeds the pipe pile length as assembled around the mandrel, the pile driving hammer is raised and 10 the mandrel extension 2 is placed on top of the mandrel 1. A pipe section 19 is placed around the mandrel and connected to the pipe section 10 by means of the collar 13 and, when the upper end of section 10 reaches the top of the earth, 15 then collar 13 is removed and the interconnection of the pipe sections is effected by means of a sleeve 21 (Fig. 2).

In the driving of my pipe pile and the spud-fitted mandrel, the hammer is stopped when the 20 foot of spud 4 reaches the rock stratum. The locking collar 13 is then released from the mandrel 1 and the pipe 10 is forced down to the rock as shown by the dotted lines 23 in Fig. 1, in which position, as shown in dotted lines in Fig. 1 and in full lines in Fig. 2, the lower edge of ring 3 is driven into the rock. Preferably, this driving down of pipe 10 is accomplished by first raising the mandrel 1 until its bottom face is flush with the driving edge of ring 3, whereupon the locking collar 13 is again fastened to the mandrel and driving is resumed. Where it is necessary to use the second pipe section 19, the latter is placed around the mandrel 1 or its extension 2 until its lower edge rests in a recess 22 of the collar 13, whereupon driving is 30 resumed on top of the pipe section 19.

Upon completion of the driving operation, the mandrel is removed from the pipe and the latter is filled up with concrete.

40 Fig. 5 illustrates a spud 18 having a sharper taper than the spud 4 shown in Fig. 1. This type of spud should be used where the earth obstruction is of such character as to make impossible the use of a spud with a flat driving 45 face.

Since the driving ring 3 is substantially an integral part of the lower edge of the pipe 10, it protects the latter against damage as earth obstructions are encountered and it provides also 50 a thicker driving edge against the final rock surface, as distinguished from the usual open-ended pipe pile in which the driving edge is readily distorted and does not form a good seal with the rock strata. Owing to this a lighter pipe pile wall 55

thickness is permissible than in the case of open-ended piles and in spite of this the driving strains will not damage the pipe.

The mandrel 1 fitted with the driving spud 4 closes the bottom of the pipe 10 and breaks up or forces aside obstructions encountered during the driving, causing the displaced earth to consolidate around the pile pipe. The earth walls will thus be strengthened, affording a lateral stability to the pile in its function as a supporting column. When an open-ended pile is driven into the earth a core of earth will accumulate in it which then must be removed by means of compressed air and water. This is not only a costly operation, but owing to the removal of this core the stability of the column is lessened to such an extent that the lateral support between its bottom and its top is negligible.

What is claimed is:

20 1. In a pipe pile construction, a driving mandrel, a driving point at its lower end, a pipe section surrounding the lower part of said mandrel, a driving ring on the lower edge of said pipe section, a collar surrounding said pipe section and having a recess in which the upper end of said pipe section is seated, a second pipe

section seated on said collar and surrounding the upper part of said mandrel, said second section being held in alignment by said collar with the first mentioned pipe section, and a removable connection between the collar and the mandrel.

2. In a pipe pile construction, a driving mandrel, a driving point at its lower end, a pipe section surrounding the lower part of said mandrel, a driving ring on the lower edge of said pipe section, a collar surrounding and seated on top of said pipe section, means for fastening said collar to said mandrel, and a second pipe section seated on said collar and surrounding the upper part of said mandrel. 15

3. In a pipe pile construction, a driving mandrel, a driving point at its lower end, a pipe section surrounding the lower part of said mandrel, a second pipe section surrounding the upper part of said mandrel, means for seating said second pipe section on top of the first mentioned pipe section and in alignment therewith, and means for fastening the assembly of the two pipe sections and said means to said mandrel. 20
